PACKAGE FOR RAZOR BLADES

Raymond W. Cook, Bristol, Conn.

Application August 4, 1932. Serial No. 627,407

12 Claims. (Cl. 206—16)

In packaging razor blades according to the prevalent practice, each blade is wrapped in a folder of oiled or other moisture-repellent paper, and thus wrapped is encased in an envelope. 5 A plurality of the blades thus treated, usually multiples of five or ten of the blades, is sealed up in a cardboard box to produce the completed sales package.

In preparing a blade so wrapped for use in a 10 blade holder, it is necessary to take the encased blade from its cardboard box, remove it from its envelope, and finally strip from it the paper wrapper referred to. Obviously, these operations are more or less tedious, particularly when one 15 is in a hurry, and the envelope and wrapper referred to must be disposed of in some manner, which often constitutes something of a nuisance. Moreover, in removing the wrapper the cutting edges of the blade are apt to be dulled by the 20 sliding of the wrapper over them.

Furthermore, no provision is made in razor blade packages of the kind referred to, for disposal of used blades, and although in some wash-rooms and bathrooms, such as those in sleeping-cars, hotels and clubs, wall slots and similar 25 means are provided for disposal of used blades, the bathrooms of private homes or residences are seldom provided with any such means, and the disposal of used blades constitutes quite a 30 problem.

The present invention relates to a package for razor blades in which the blades may be packed without the use of the customary oiled or other paper wrappers and envelopes, and in which 35 means are provided for disposal of the used blades.

The invention consists in a package for razor blades, particularly safety razor blades of the now familiar double-edged type provided with 40 offstanding portions at their ends; this package comprising a box having a bottom, a cover, and a side wall forming the sides and ends of the box, the box being provided at one end adjacent to its bottom with an aperture preferably in the 45 form of a relatively narrow slot of sufficient extent to permit the passage through it of a blade, and through which the used blades may be successively inserted into the box beneath a stack of unused or new blades contained therein. The 50 box is so designed, moreover, that its sides are spaced apart at a distance greater than the breadth of a razor blade between its cutting edges, and the ends of the box are provided with offsets to receive the offstanding portions of the 55 blade ends to so position the blades within the box that their cutting edges do not contact with the box sides and are therefore guarded against injury. Moreover, the bottom of the box carries means whereby when a used blade is inserted 60 in the box it cannot escape therefrom through the

slot. And the invention consists further in the provision of a separator or follower member of a particular form and having particular characteristics, inserted in such position in the box as to separate the unused from the used blades, all 65 as will be explained hereinafter more fully and finally claimed.

In the accompanying drawing illustrating the invention, in the several figures of which like parts are similarly designated,

Fig. 1 is a top perspective view of the package of the invention, looking at the end in which the slot is provided;

Fig. 2 is a view similar to Fig. 1 but with the cover of the box opened;

Fig. 3 is a bottom perspective view of the package showing a used blade being inserted thereinto through the slot;

Fig. 4 is a plan view of the package with the cover raised;

Fig. 5 is a longitudinal section of the package taken substantially on the line 5—5 of Fig. 4 and showing the cover opened and a blade being removed;

Fig. 6 is a section similar to Fig. 5 but with the cover closed, a used blade being inserted through the slot, and illustrating the manner in which the unused or new blades are displaced upwardly by the used blades as the latter are successively inserted through the slot;

Fig. 7 is a plan view of the box with the cover opened and showing two positions of a blade as it is inserted through the slot; and

Fig. 8 is a perspective view on a small scale of the box with the cover open and showing the 95 box provided with blade-retaining guards.

As hereinbefore indicated, the package comprises a box having a bottom 1, a cover 2, and a side wall preferably integral with the bottom and upstanding therefrom to provide the sides 100 3 and ends 4 of the box.

The cover 2 is preferably suitably hinged, as indicated at 5, to one side of the box and is provided with a spring or snap catch 6 for engagement with an offstanding lug 7 formed upon the 105 opposite side of the box.

The bottom 1 of the box is provided with a plurality of inwardly projecting lugs 8 arranged in pairs transversely of the box and upon these lugs, when the package is a fresh package, bears 110 a separator or follower member 9 composed of fiber board, cardboard or other relatively absorbent material of such contour as to closely fit the sides and ends of the box, and upon this member 9 rests the stack of blades 10. The 115 blades are not provided with any envelopes or other wrappers but are preferably treated with some moisture-repellent or rust-preventing substance, such as petrolatum or other similar coating material.

120

The blades, as shown, are of a more or less familiar or conventional type having two cutting edges 11, longitudinal openings or slots 12 and 13 and offstanding end portions 14.

5 As will be apparent from an inspection particularly of Figs. 2 and 4, the ends 4 of the box are provided with offsets 15 of such shape as to relatively closely confine the offstanding end portions 14 of the blades and thus hold the blades 10 in such position within the box that their cutting edges 11 cannot become dulled by contact with the sides of the box.

It will be seen that the combined thickness of the separator or follower member 9 and the 15 stack of blades 10 is such as to completely fill the box, and thus when a blade is removed from the top of the stack sufficient room is left for insertion below the separator or follower member of a used blade without crowding the blades 20 in the box.

By packaging the blades in the manner thus far described, it will be seen that by opening the cover and depressing one end of the stack of blades, the lugs 8 adjacent to the end depressed 25 will act in combination as a fulcrum to raise the other end of the stack of blades so that a blade may be slid off of the stack over the end of the box ready for use without the necessity of removing therefrom the troublesome protecting 30 coverings now commonly employed. After a blade has been thus removed from the package the cover is preferably closed.

The blade which had previously been in use must now be disposed of in some manner. 35 With this in view, one end of the box is provided with a slot 16 of relatively narrow form but of sufficient extent to make easy the insertion of a blade therethrough. The used blade may, therefore, be inserted through this slot and 40 into the box beneath the separator or follower member 9, and coming in contact with the nearest pair of lugs 8 will, due to the cam-like form of these lugs, be guided into easy sliding engagement with the under face of the follower member 45 9, or, if other used blades have already been inserted into the box, into engagement with such blades, as illustrated in Fig. 6.

As will be seen by reference to Fig. 7, the corners of the box and the bends joining the offsets 50 15 to the ends of the box are made with such curvatures as to effectively guide a blade inserted through the slot into such position that its off-standing end portions 14 will engage with the offsets 15 of the box. Thus, even though the blade 55 is inserted through the slot out of alignment with the longitudinal axis of the box, as illustrated in full lines in Fig. 7, this curved formation of the box ends will guide it to its proper position in the box, as shown in broken lines in Fig. 7.

60 Obviously, once a blade has been fully inserted into the box, the lugs 8 will so position it relatively to the bottom 1 thereof and to the slot 16 that it will abut at both of its ends against the ends of the box and cannot escape therefrom 65 through the slot.

Thus, as new blades are removed from the top of the stack of blades 10, used blades may be inserted through the slot beneath the separator or follower member 9 upon which the new or used 70 blades are supported, and the unused blades will thus be given a step-by-step or progressive upward movement which will bring them successively into position for easy removal from the box.

75 In some cases, used blades which still bear

lather or are otherwise moist will be inserted into the box, and in order to guard against contamination or rusting of the new or unused blades due to the moisture thus introduced into the box the separator or follower member 9 is preferably permeated or otherwise appropriately treated with some moisture-repellent substance, and, due to such treatment and to the close contact of its edges with the sides and ends of the box, the moisture cannot pass above it and injure the new or unused blades. Moreover, in a new package, the separator or follower member 9 will prevent moisture which might enter the box through the slot 16 from reaching the blades.

80 In order to facilitate the removal of the new or unused blades from the box, the offset portions of the ends thereof may be provided at their top edges with slight recesses 15'; and in order that the insertion of the used blades may be facilitated, the bottom 1 of the box may be 85 recessed adjacent to the slot or aperture 16 therein as indicated at 16'.

To prevent the blades from falling from the box, in case the box should be upset when the cover is open or in case the box should be dropped 100 and the cover spring open, the upper edges of the sides of the box may be formed with inwardly-extending guards 17, as shown in Fig. 8 of the drawing.

105 It will thus be seen that this invention provides a package for razor blades which furnishes complete protection not only against rusting and damage to the edges of the blades but which makes unnecessary the wrapping of the blades now commonly practiced. Moreover, the package 110 provides for easy removal of new blades, and a ready means for disposal of the used blades as the new blades are removed therefrom. Also, when all of the blades have been used and replaced in the box, the whole package may be thrown away, 115 if desired, without the now present danger to persons who must handle the trash or rubbish in which the discarded blades may be included.

120 Various changes and modifications are considered to be within the spirit of the invention and the scope of the following claims.

I claim:

1. A package for safety razor blades, comprising a box having a bottom, a cover, and a side wall, said side wall providing sides and ends for the box, said box adapted to receive a plurality of blades in stacked relation, one end of said box provided with an aperture through which used blades may be inserted into the box adjacent to its bottom, and means provided in the bottom of the box for supporting the used blades in such position relatively thereto that they cannot escape through said aperture after insertion into the box.

125 2. A package for safety razor blades, comprising a box having a bottom, a cover, and a side wall, said side wall providing sides and ends for the box, said box adapted to receive a plurality of blades in stacked relation, one end of said box provided with an aperture through which used blades may be inserted into the box adjacent to its bottom, and means provided in the bottom of the box and extending into the box above the surface of said bottom to a height greater than the height of said aperture, said 130 means adapted to support the used blades in such position relatively to said aperture that they cannot escape therethrough after they have been fully inserted into the box.

135 3. A package for safety razor blades, com-

- prising a box having a bottom, a cover capable of being opened to give access to the interior of the box, and a side wall, said side wall providing sides and ends for the box, said box adapted to receive a plurality of blades in stacked relation, one end of said box provided with an aperture through which used blades may be inserted into the box adjacent to its bottom, and means provided in the bottom of the box for supporting the used blades in such position relatively thereto that they cannot escape through said aperture after insertion into the box, said means serving as a fulcrum upon which the stacked blades may be tilted to raise an end of the topmost blade above the side wall and permit such blade to be pushed out of the box. 5
4. A package for safety razor blades, comprising a box having a bottom, a cover, and a side wall, said side wall providing sides and ends for the box, said box adapted to receive a plurality of blades in stacked relation, one end of said box provided with a slot adjacent to the box bottom and through which used blades may be inserted into the box, a plurality of lugs provided in the bottom of said box and projecting into the box to a height greater than the slot opening, said lugs adapted to support the used blades inserted into the box in such position that they cannot escape through said slot, and a separator member arranged at the bottom of the stack of unused blades and adapted to separate the unused blades from the used blades. 10
5. A package for safety razor blades, comprising a box having a bottom, a cover, and a side wall, said side wall providing sides and ends for the box, said box adapted to receive a plurality of blades in stacked relation, one end of said box provided with a slot adjacent to the box bottom and through which used blades may be inserted into the box, a plurality of lugs provided in the bottom of said box and integral therewith and projecting into the box to a height greater than the slot opening, said lugs adapted to support the used blades inserted into the box in such position that they cannot escape through said slot, and a separator member arranged at the bottom of the stack of unused blades and adapted to separate the unused blades from the used blades. 15
6. A package for safety razor blades, comprising a box having a bottom, a cover, and a side wall, said side wall providing sides and ends for the box, said box adapted to receive a plurality of blades in stacked relation, one end of said box provided with a slot adjacent to the box bottom and through which used blades may be inserted into the box, a plurality of lugs provided in the bottom of said box and projecting into the box to a height greater than the slot opening, said lugs adapted to support the used blades inserted into the box in such position that they cannot escape through said slot and so formed as to provide cam surfaces upon which the blades thus inserted may be guided to appropriate position within the box, and a separator member arranged at the bottom of the stack of unused blades and adapted to separate the unused blades from the used blades. 20
7. A package for safety razor blades of the double-edged type provided at their ends with offstanding portions, said package comprising a box adapted to receive a plurality of blades in stacked relation and having a bottom, a cover, and a side wall, said side wall providing sides and ends for the box, offsets in the ends of the box complementary to and adapted to receive the offstanding portions of the blade ends, and one end of said box being provided with an aperture through which used blades may be inserted into the box, the portions of the box ends adjacent to said offsets being curved in contour and merging into the offsets and into the sides of the box, whereby a blade inserted through said aperture will have its offstanding end portions so guided as to register with the offsets of the box ends. 25
8. A package for safety razor blades, comprising a box adapted to receive a plurality of blades in stacked relation, means whereby used blades may be inserted within the box adjacent to the stacked blades therein, and a separator member fitting closely within the box and contacting with the sides and ends thereof and so positioned as to separate the used blades from the unused blades, said separator member due to its contact with the sides and ends of the box preventing possible transmission of moisture around its edges from the used blades to the unused blades. 30
9. A package for safety razor blades, comprising a box adapted to receive a plurality of blades in stacked relation, means whereby used blades may be inserted within the box adjacent to the stacked blades therein, and a separator member fitting closely within the box and contacting with the sides and ends thereof and so positioned as to separate the used blades from the unused blades, said separator member treated with a moisture-repellent material and due to its contact with the sides and ends of the box preventing possible transmission of moisture around its edges from the used blades to the unused blades. 35
10. A package for safety razor blades, comprising a box having a bottom, a cover, and a side wall, said side wall providing sides and ends for the box, said sides of the box formed with inwardly-projecting guards, said box adapted to receive a plurality of blades in stacked relation, one end of said box provided with an aperture through which used blades may be inserted into the box adjacent to its bottom, and means provided in the bottom of the box for supporting the used blades in such position relatively thereto that they cannot escape through said aperture after insertion into the box. 40
11. A package for safety razor blades, comprising a box having a bottom, a cover, and a side wall, said side wall providing sides and ends for the box, said box adapted to receive a plurality of blades in stacked relation, said cover capable of being opened to afford access to said blades for removal of same, and means forming a part of said box and overlying the stacked blades to prevent accidental displacement or escape of same when the cover is raised. 45
12. A package for safety razor blades, comprising a box having a bottom, a cover, and a side wall, said side wall providing sides and ends for the box, said box adapted to receive a plurality of blades in stacked relation, said cover capable of being opened to afford access to said blades for removal of same, and guard means carried by said side wall and overlying the stacked blades to prevent accidental displacement or escape of same when the cover is raised. 50
